(57) CLAIM

The ornamental design for a stretchable notebook computer case, as shown and described.

DESCRIPTION

FIG. 1 is a front perspective view of a stretchable notebook computer case showing my new design;

FIG. 2 is a front perspective view thereof shown in a partially open position;

FIG. 3 is a top plan view thereof;

FIG. 4 is a front elevation view thereof;

FIG. 5 is a bottom plan view thereof;

FIG. 6 is a right elevation view thereof;

FIG. 7 is a rear elevation view thereof; and,

FIG. 8 is a left elevation view thereof.

The dashed lines in FIG. 2 represent environment and form no part of the claimed design.
